UNITED STATES PATENT OFFICE.

DALLAS J. BRANNING, OF HAWLEY, PENNSYLVANIA.

DESIGN FOR A FAN-SCALLOPED DISH.

41,205.

Specification for Design.

Patented Feb. 28, 1911.

Application filed December 16, 1910. Serial No. 597,719. Term of patent 3½ years.

To all whom it may concern:

Be it known that I, DALLAS J. BRANNING, a citizen of the United States, and resident of the city of Hawley, county of Wayne, and State of Pennsylvania, (whose post-office address is Hawley, Pennsylvania,) have invented a new, original, and ornamental Design for a Fan-Scalloped Dish, of which the following is a specification.

Reference is to be had to the accompanying drawing in which the figure is a side elevation of a fan scalloped dish embodying my design.

I claim:

The ornamental design for a fan scalloped dish as shown herein.

Signed at the city of Hawley, county of Wayne, and State of Penna., this 8 day of December, 1910.

D. J. BRANNING.

Witnesses:

R. W. MURPHY,
J. S. PENNELL.

Copies of this design may be obtained for five cents each, by addressing the "Commissioner of Patents, Washington, D. C."
